UNITED STATES PATENT OFFICE.

HERMAN C. PRIEBE, OF BLUE ISLAND, ILLINOIS.

AUTOMATIC AIR-SIGNAL, AIR-BRAKE, AND STEAM COUPLING.

No. 857,362.

Specification of Letters Patent.

Patented June 18, 1907.

Application filed March 20, 1907. Serial No. 363,468.

To all whom it may concern:

Be it known that I, HERMAN C. PRIEBE, a citizen of the United States, residing at Blue Island, Cook county, Illinois, have invented 5 certain new and useful Improvements in Automatic Air-Signal, Air-Brake, and Steam Couplers, of which the following, taken in connection with the drawings, is a description.

10 The primary object of my invention is the production of a combined air signal, air brake and steam coupler for railway cars, one of which is carried by and operated automatically and simultaneously with the car coupler in the coupling and uncoupling of trains.

The device is entirely automatic in its operation and is coupled and uncoupled with the operation of the car coupler, which may 20 be accomplished without the necessity of a person going between the cars to make the connection or disconnection.

With these and other objects in view the present invention consists in the combination 25 and arrangement of parts, as will be hereinafter more fully described, shown in the drawings and pointed out in the claims, it being understood that changes in form, proportion and minor details may be made 30 within the scope of the claims without departing from the spirit or sacrificing any of the advantages of the invention.

In the accompanying drawings Figure 1 is a top plan view of the co-operating parts of 35 my coupler, showing the parts in opened position; Fig. 2 is a like view showing the parts in closed position; Fig. 3 is a side elevation of the same illustrating the means of supporting said couplers upon the knuckle pins of the 40 car couplers; Fig. 4 is a sectional detail taken on line 4—4 of Fig. 2; Fig. 5 is a detail partly in section taken on line 5—5 of Fig. 4. Fig. 6 is a sectional detail taken on line 6—6 of Fig. 3.

45 In carrying out my invention A, A', represent the knuckle pins extending downwardly from the car couplers A² and carrying therein the two halves or sections B, B' of my coupling device. Each of the halves or sections 50 B, B' is provided with a vertical annular opening B², through which the knuckle pins extend. This annular opening is of smaller diameter mediate of the length thereof than at the ends, which allows the coupling pins 55 to have a slight sidewise motion to accommodate themselves to the movement of the

train. Each half of the coupler B, B' is provided with a bifurcated projection C, C' on one side thereof and a recess or groove c, c' upon the other side. One edge of each of the grooves c, c' is upturned and rounded outwardly, as at d, d' to form a guide for the projecting members C, C'. Through each of the upturned edges d, d' is an aperture d², d³ into which is secured a chain D, D' extending 65 to the bosses d⁴, d⁵ which are made integral with the draw bar A².

Projecting from the body of the couplers B, B' are the bosses e, e', e², e³. Springs E, E' surround the pins A, A', above the couplers B, B' and extend through the bosses e, e² 70 and e', e³ respectively, outside of the coupler body to the bottom of the pins A, A'. The tension of these springs is to hold the two halves or sections of the coupler together. 75

F, F' are braces, each of which is secured at one end thereof to the drawbar of the coupler A²; the opposite end is bent at right angles to itself and has an aperture through which one of the pins A, A' extends. A cotter pin f, f' extends through each of the 80 knuckle pins A, A' beneath the brace.

A plurality of annular openings G, G', G² extend through the sections B, B' and when the couplers are brought together the set of 85 openings in each section coincides with the corresponding set of the other section, and forms a continuous passageway through the coupler. Pipes g are screwed into or otherwise secured to the coupler sections and are 90 extended to the signal, brake or steam connections on the car. As is obvious the openings G, G', G² may be of any size and dimensions required for the purpose.

h, h', h² are flexible gaskets surrounding 95 the meeting faces of the air pipes to form an air tight connection between the sections when the coupler is closed. The pipe G² used for the steam connection is extended inside of the coupler section as shown in Fig. 6 100 and is provided upon the outside thereof with the flanges g², g³ which are secured by screws or otherwise directly to the coupler section.

The operation of the device is as follows: 105 As the cars are coupled and uncoupled in the usual way the two sections of my coupler are brought together automatically and simultaneously, the flexible washers forming a complete closure of the openings which are coincident with each other. The tension of 110 the springs E, E' being exerted upon the outside of each coupler section holds said sec-

tions together under the stress and strain due to the movement of the car. When the car is uncoupled the sections are separated with it, the chains D, D' holding the sections in a straight line with that of the knuckle pins, so that it will readily unlock when the knuckles of the coupler open.

I contemplate the use of my invention upon freight cars as well as passenger trains, but in this instance the steam or signal hose will not be required, and the couplers will have only one opening through which the air brakes are operated. The couplers will be made to interchange and operate the air brakes as on passenger, express or mail trains, but will have no openings for the steam or air signal connections, otherwise the operation will be the same.

I claim:

- 20 1. In a coupling device, the combination of the two halves or sections, knuckle pins upon which each of said sections are supported, coiled springs surrounding said coupling pins above the sections and extending outside of each section to the bottom thereof, air and steam passages through said coupler sections, and means for providing an air tight connection between the confronting faces of said sections.
- 25 2. In a coupling device the combination of the two halves or sections, knuckle pins extending through each of said sections and having connection with the car coupler, air and steam passages through said sections, pipes connected through said passages and extending to the air and steam pipes of the car, flexible gaskets between the confronting faces of said sections, coiled springs supported by the aforesaid knuckle pins and adapted 35 to hold the two sections of the coupler together, substantially as described.
- 30 3. In a coupling device, the combination of the two halves or sections, each section having bifurcated grooves interlocking with corresponding projections on the other section, knuckle pins upon which said sections are supported, coiled springs surrounding said pins and extended outside of each of said sections, coincident air and steam 40 passages through the said sections, flexible connections between the confronting faces of said sections and means for automatically opening and closing said couplers.
- 45 4. In a coupling device, the combination of two interlocking sections, each of which has an annular opening extending vertically therethrough, said annular opening being of smaller diameter mediate of the length thereof than at the ends, supporting pins

extending through said annular opening and 60 springs for holding said sections together.

5. In a coupling device, the combination of two interlocking halves or sections each of which has an annular opening extending vertically therethrough, each section carrying 65 projections upon one side thereof and a groove or channel on the opposite side, the projections of one section fitting into the grooves of the opposite section, coincident steam and air passages through said sections, 70 pipes connected with said air passages and pipes extending approximately through the steam passages, said steam pipes having flanges abutting against the outer sides of said sections and secured thereto, substantially as described.

6. In an automatic coupling device of the class described, the combination of two interlocking sections, each of said sections having an annular opening extending vertically therethrough, said opening being of larger diameter at the ends than at the center thereof, pins extending through said openings, coincident air and steam passages through said sections, flexible gaskets between the confronting faces of the two sections, and means for automatically coupling and uncoupling said sections.

7. In an automatic coupling device, the combination of a car coupler and knuckle pins extending therethrough, with two interlocking sections supported by said coupling pins, projections extending from each of said sections and fitting into grooves or channels in the opposite section, springs bearing 95 against the outside of each section, and means for automatically opening and closing said couplers simultaneously with the car coupler.

8. In an automatic coupling device, the combination of a car coupler and the knuckle pins extending therethrough, with two interlocking sections supported upon said knuckle pins, said sections having one or more passage ways extending therethrough, springs supported upon said knuckle pins and bearing against the outside of each section, and means for automatically opening and closing said sections simultaneously with the operation of the car coupler.

In testimony whereof, I have signed this specification in the presence of two subscribing witnesses.

HERMAN C. PRIEBE.
